MARYLAND.

INDENTION DEVICE FOR TYPOGRAPHICAL MACHINES.

Application filed September 17, 1925. Serial No. 56,989.

This invention is a measure support member for matrices such as are employed in typographical machines for casting lines of type. In machines of the character mentioned, there are conditions which sometimes arise that require a blank space at one end of the line or slug technically known as indenting. In order to accomplish the casting of a metal slug for indenting, typographical machines are equipped with vise like jaws for the holding of matrices etc., which jaws must be positioned or set to suit varying measurements.

The setting of the vise jaws in present practice is accomplished by placing the proper matrices required for assembling a line upon a support member which is positioned between a movable jaw and a slide rod stop, and then shifting the movable jaw to the required position. This is objectionable because in the absence of any form of retaining means the said matrices become disengaged through vibration and drop out, thereby causing a loss of time and labor necessary to reposition the movable jaw.

One of the objects of this invention is to provide a simple means to support a number of matrices between a vise jaw and a slide rod stop on a standard typographical machine and to prevent them from falling out under the conditions above mentioned.

Another object is to provide means for indenting a line or slug whereby the indentation may be sawed off and an initial letter snugly fitted in.

In the accompanying drawing, illustrating this invention and forming a part of this specification,

Figure 1 shows a fragmentary view having the devices affixed to a part of a well known form of typographical machine of the

present commercial form. Figure 2 is a plan view. Figure 3 is a perspective view.

Referring to the drawing:

In Figure 1, 10 designates a part of a frame of a standard typographical machine, 11 is a vise jaw, and 12 is the slide rod stop of said machine. Affixed to the machine is a supporting device 13. In Figure 3, 14 designates a flange for holding matrices, etc., in place upon the graduated member 16.

The ends 17 of the graduated member 16 are shown as bent around the contiguous portions of base 15 to retain said graduated member in place.

In operating this device, the desired initial matter to be used in place of the indentation is placed upon the support and securely held between the vise jaw 11 and the slide rod stop 12, thereby preventing the dislodgment of matrices or other characters as is now the case in present practice.

Having described the invention what we claim is:

In a typographical machine, a device for forming indented type slugs by holding measuring means between the stop rod and movable vise jaw, the combination of a vise frame base, provided with a measure support, comprising a horizontal base, having a retaining flange at one edge, and a supporting flange at the other edge provided with screw openings, said support being devoid of obstructions at the ends so the stop rod of a typographical machine may move freely thereover, and securing means passing through said supporting flange opening, into the base frame screw openings.

In testimony whereof we have hereunto set our hands.

BERNARD M. NEES.
Z RUBOTTOM.
